CLAIM

The ornamental design for a ground mounted trailer stand, as shown and described.

DESCRIPTION

FIG. 1 is a perspective view of a ground mounted trailer stand in a closed position showing our new design;

FIG. 2 is a top view thereof;

FIG. 3 is a front view thereof, the rear view being identical;

FIG. 4 is a right side view thereof, the left side view being identical;

FIG. 5 is a bottom view thereof, the bottom view of the ground mounted trailer stand in an opened position being identical;

FIG. 6 is a perspective view of the ground mounted trailer stand in an opened position;

FIG. 7 is a top view thereof;

FIG. 8 is a front view thereof, the rear view being identical; and,

FIG. 9 is a right side view thereof, the left-side view being identical.
